UNITED STATES PATENT OFFICE.

OLIVER J. MOUSSETTE, OF BROOKLYN, NEW YORK.

BRICK-MACHINE.

1,335,071.

Specification of Letters Patent. Patented Mar. 30, 1920.

Application filed September 28, 1915. Serial No. 53,063.

To all whom it may concern:

Be it known that I, OLIVER J. MOUSSETTE, a citizen of the United States, residing at Brooklyn, in the county of Kings and State 5 of New York, have invented certain new and useful Improvements in Brick-Machines, of which the following is a specification.

The invention has relation to the type of 10 machines for making bricks or like building units which involve an intermittently rotated table provided with molds, a plunger for compressing the material in the molds, an endless carrier for feeding pallets into 15 position for receiving the bricks and for delivering the formed bricks from the machine, and an ejector for dislodging the bricks from the molds.

One object of the invention is to provide 20 a machine for forming bricks or like articles which relieves the frame-work of the strain incident to the compressing of the material in the formation of the brick, such strain being neutralized upon the shaft 25 which operates the compressing elements, said elements being arranged so as to compress the material between them.

The invention further aims to provide 30 means whereby the mold disposed between the compressing elements is free to move when said elements are separated, the parts being so arranged that when the compressing elements are moved apart the mold is advanced, thereby bringing the next succeeding mold in position to have the material compressed for forming the brick and the brick previously formed brought into 35 position to be removed from the mold.

A further purpose of the invention is to 40 obviate wear upon the bricks while moving from the compressing mechanism to the ejector and at the same time relieving the bed from wear and preventing the dragging of the brick thereover.

The invention also contemplates novel 45 actuating means for uncovering the bottom of the mold at the proper time to insure delivery of the brick from the mold, and again covering the bottom of the mold preliminary to placing material for forming the 50 next brick in the mold.

The invention also has for its object the provision of a novel mounting of the table whereby the table may move easily and the 55 mounting will be protected from the accumulation of foreign matter which would

tend to clog the parts and interfere with the proper operation of the machine.

The invention also aims to operate the endless carrier and rotary table in unison 60 thereby preventing any dragging motion or unnecessary expenditure of power in the operation of the machine.

The invention furthermore has for its object to devise a machine which in operation 65 will form a plurality of bricks at a single operation, all of such bricks being delivered from the mold with sharp and well defined corners.

Another purpose of the invention is to so 70 dispose the magazine that the pallets are supported partially by the same, thereby enabling the carrier to be operated by a less force and wear than is the case where the pallets are supported with the entire weight 75 resting upon the carrier.

The invention also has for its object to devise novel actuating means for the platen which may be readily adjusted to insure positive engagement between the platen and 80 the slide closing the bottom of the mold in which the material is compressed, and also to provide positive actuating means for the several working parts and to have such actuating means disposed so as to be readily 85 accessible for replacement or other purposes.

With the foregoing and other objects in view the invention may be said to consist 90 of the novel features, details of construction and combinations of parts which hereinafter will be more particularly set forth, illustrated in the drawings hereto attached and subsequently claimed.

Referring to the drawings,

Figure 1 is a perspective view of a brick 95 making machine embodying the invention:

Fig. 2 is a top plan view of the machine, parts being broken away;

Fig. 3 is a vertical central section on the 100 line 3—3 of Fig. 2, looking in the direction of the arrows;

Fig. 4 is a vertical central section on the line 4—4 of Fig. 2, looking in the direction 105 of the arrows;

Fig. 5 is an enlarged sectional detail on the line 5—5 of Fig. 3, looking to the left as designated by the arrows;

Fig. 6 is an enlarged detail view of the 110 ejector and platen coöoperating therewith showing a portion of the endless carrier, the actuating means for the platen and a por-

tion of the mold and frame-work, the latter parts being in section;

Fig. 7 is a detail section on the line 7—7 of Fig. 6, looking to the right as designated by the arrows;

Fig. 8 is an enlarged sectional detail of the magazine for holding the pallets showing a portion of the track and endless carrier;

10 Fig. 9 is an enlarged detail perspective view of the means for holding the rotary table stationary prior to and during the operation of the compressing means for forming the brick;

15 Fig. 10, is a horizontal sectional detail of a portion of the rotary table and frame-work showing more particularly the means for intermittently operating the table and the anti-friction devices between the rotary 20 table and the part of the frame about which such table rotates;

25 Fig. 11 is a view in elevation of a portion of the frame-work the rotary table and the means for transmitting movement to such table;

Fig. 12 is an enlarged top plan view of a portion of the rotary table and frame-work showing more clearly the means for operating the slides or bottoms of the molds;

30 Fig. 13 is an enlarged detail of the means for moving the machine by hand when it is required to set or adjust the same;

Fig. 14 is an enlarged detail perspective of the lever for operating the platen 35 operating with the ejector;

Fig. 15 is an enlarged detail view of a portion of the gearing for operating the endless carrier;

40 Fig. 16 is a sectional view of a portion of the table showing a mold and follower;

Fig. 17 is a top plan view of the follower showing the means coöperating therewith for withdrawing the same from the mold;

45 Figs. 18 and 19 are detail views of modified forms of gearing for imparting a variable rotary movement to the table.

The main frame comprises a pedestal 1, a base 2, a tower 3 and offstanding or bracket portions 4, 5 and 6. The pedestal 50 portion 1 of the frame is provided at its top with a horizontal portion 7 forming a bed upon which an annular member 8 is rotatably mounted, such member constituting the table which is provided at regular intervals with mold cavities or openings in which are fitted molds 9. The tower 3 is centered upon the pedestal 1 and secured thereto in any substantial way and is formed at its lower end with an outwardly extending 55 flange 10 which is of circular outline and is elevated slightly above the bed 7. The rotary table 8 is formed upon its inner wall with a flange 11 which slightly under laps the outer portion of the flange 10. Anti-friction devices are interposed between the

inner circular wall of the rotary table 8 and the outer vertical edge of the flange 10. These anti-friction devices preferably consist of rollers 12, the same being supported upon the inwardly extending flange 11. A 70 cap ring 13 secured to the flange 10 extends across the space formed between the table 8 and flange 10 and retains the rollers 12 in position and at the same time serves to maintain a close joint to prevent sand, clay 75 or other foreign substance from entering the space and interfering with the operation of the moving parts. The outer edge of the table 8 is grooved and the bottom of such groove is formed with cog teeth 14 which are adapted to coöperate with the toothed portion of a mutilated gear wheel 15. In the operation of the machine the table 8 is intermittently rotated so as to bring the molds successively into position for proper operation 80 of the compressing devices upon the brick forming material deposited in such molds. The gear wheel 15 makes one complete revolution for each actuation of the rotary table and the cog gearing between the 85 parts 8 and 15 is of such relative construction and arrangement as to insure a proper movement of the table at each operation thereof. The mutilated gear wheel 15 is secured to a vertical shaft 16 which is located 90 at one side of the machine and is mounted at or near its ends in suitable bearings, as indicated most clearly in Fig. 1.

Arranged to coöperate with the molds is a plunger 17 and a platen 18, each being 100 mounted to receive a vertical reciprocatory movement and directed in its movements by any approved form of guide. The plunger 17 is located above the rotary table whereas the platen 18 is disposed in vertical alignment with the plunger beneath the rotary table and they receive a simultaneous movement in opposite directions whereby they advance or move apart, the material in the mold being compressed during the advance. 105 The platen 18 is mounted upon the guide rods 19. The plunger 17 is mounted in guides 20 attached to a side of the tower 3. A main shaft 21 is mounted in suitable bearings forming a part of the main frame and is provided with eccentrics 22 and 23 with which the usual eccentric straps are arranged to coöperate. A pitman 24 connects the eccentric 22 with the plunger 17. Pitmen 25 connect the eccentrics 23 with 110 the platen 18 or a pin 26 passing through such platen and having its projecting ends connected with the lower ends of the pitmen 25. The eccentrics 22 and 23 have an opposite arrangement, that is, when the eccentric 22 is operating to depress the plunger 17 the eccentrics 23 are operating at the same time to move the platen 18 upward, with the result that the plunger and platen are moved simultaneously in oppo- 115 120 125 130

site directions. As a result of this arrangement of the eccentrics the frame-work of the machine is relieved of all strain incident to the compression of the material during the 5 formation of the brick, such strain being imposed directly upon the main shaft 21 and neutralized thereon by the opposite movement of the plunger and platen.

The bricks are dislodged from the molds 10 by an ejector comprising a plunger 27 which is mounted to reciprocate in a guide 28 located at one side of the tower 3. A pitman 29 is attached at its lower end to the plunger 27 and is connected at its upper 15 end to a crank 30 secured to one end of a shaft 31 which is mounted in a suitable bearing forming part of the frame-work. The shaft 31 is geared to the main shaft 21 and for this purpose is shown as provided at its 20 inner end with a bevel gear 32 which meshes with a bevel gear 33 secured to the main shaft 21. Coöperating with the plunger 27 is a platen 34 which is mounted to receive a vertical reciprocatory movement, being 25 directed in its vertical movements by means of a suitable guide 35 attached to or forming a part of the main frame. The platen 34 is elevated when receiving the brick from the mold thereby preventing any jar which 30 would tend to distort or mar or otherwise injure the brick by dropping a distance after being forced from the mold by the plunger. After the platen 34 has received the brick from the mold it descends so as 35 to place the pallet containing the brick upon the track over which it is moved in its delivery from the machine.

The platen 34 is carried by a stem 36 which is mounted in the guide 35. One end 40 of the operating lever enters an opening 37 formed in the stem 36 and said lever comprises two members 38 and 39, both loosely mounted upon a shaft 40. The members 38 and 39 have a relative adjustment and for 45 this purpose the member 38 is formed with laterally extending spaced ears 41 in which are fitted adjusting screws 42. The member 39 has an extension 43 which projects into the space formed between the ears 41 and is adapted to be engaged by the inner 50 ends of the adjusting screws 42. It follows that by backing one of the adjusting screws 42 and advancing the other adjusting screw the members 38 and 39 of the lever 55 may be relatively adjusted so as to insure moving the platen 34 to a position to obtain the best results when elevated to the limit of its throw by the means operating the said lever. The member 39 is provided at one 60 side with a roller 44 to travel upon a cam 45 secured to a shaft 46. By this means the outer end of the lever is elevated thereby depressing the platen 34 and depositing the brick dislodged from the mold upon the 65 track in position to be delivered from the

machine. The lever is counterbalanced by means of a weight 47 which is adjustable upon a rod 48 attached to the outer end of the lever. The weight 47 is of such mass and position with reference to the lever as 70 to over-balance the platen 34 and the weight of the brick thereon. This arrangement provides for a slight movement of the platen 34 so as to obviate any jar and prevent any possible injury to the brick. 75

A track 49 is arranged at one side of the machine and below the plane of the rotary table and its supporting bed 7. This track may be supported in any substantial manner and of any preferred length and construction providing it comprises two rails which are transversely spaced and so disposed as to receive opposite ends of the pallets 50. An endless carrier 51 is arranged in the same vertical plane with the track and is 80 adapted to move the pallets along the track into position to receive the bricks as they are dislodged from the mold and to deliver the bricks from the machine as they are formed. The endless carrier 51 comprises 85 companion chains or belts which are supported at opposite points by means of sprocket wheels 52 and 53. The sprocket wheels 52 and 53 are provided in pairs and are secured to shafts 54 and 55 whereby the 90 sprocket wheels of each pair rotate in unison. In the operation of the endless carrier the upper run travels from right to left and in order that the upper run of the endless carrier may be operated by means of a pulling 95 force rotary movement is positively applied to the shaft 54. This arrangement keeps the upper run of the endless carrier 100 taut and prevents any buckling thereof which would be the tendency if the shaft 105 55 were positively rotated and the upper run of the endless carrier moved by a pushing force. Certain links of the endless chains comprising the carrier 51 are provided with projections 56 which are adapted to engage 110 the rear edge of a pallet 50 and move the same along the track 49. The projections 56 are located upon opposite sides of the 115 chain or belts comprising the carrier and extend upwardly along opposite sides of the members comprising the track 49 as indicated most clearly in Fig. 7. This arrangement of the projections 56 results in maintaining the endless members of the carrier 120 in line with the members comprising the track.

The shaft 54 is provided with a gear wheel 57 which is adapted to be engaged by the toothed portion of a mutilated gear 58 secured to one end of a shaft 59, the opposite 125 end of such shaft having a gear wheel 60 attached thereto which is in mesh with a gear wheel 61 secured to the shaft 46. The shaft 46 is provided at one end with a bevel gear 62 which is in mesh with a bevel gear 130

63 fastened to one end of a shaft 64 which, in turn, is provided at its opposite end with a bevel gear 65 meshing with a bevel gear 66 attached to the lower end of the vertical shaft 16, said shaft 16 being provided at its upper end with a bevel gear 67 which is in mesh with a bevel gear 68 attached to a horizontal shaft 69 mounted in suitable bearings at the top of the frame-work. A gear wheel 10 70 secured to the shaft 69 is in mesh with a gear wheel 71 fastened to the main shaft 21. A gear wheel 72 secured to the main shaft 21 is in mesh with an idler 73 which in turn is in mesh with a pinion 74 secured to a shaft 15 75 upon which a bevel gear 76 is secured and which meshes with a pinion 77 fastened to a drive shaft 78. A band pulley 79 is secured to the shaft 78 and is adapted to receive motion from a suitable source of power 20 by means of a drive belt 80. The gear wheel 58, being mutilated, imparts an intermittent movement to the gear wheel 57, hence intermittently actuates the endless carrier. The gearing is so timed as to insure 25 a movement of the endless carrier whereby a pallet 50 is brought into position above the platen 34 an instant prior to the upward movement of the platen to lift the pallet into position to receive the brick as 30 the same is ejected from the mold. When the platen 34 descends and deposits the pallet carrying the brick upon the track 49 the endless carrier is again actuated to move the brick carrying pallet forward and at the same time bring the next empty pallet into 35 position to be elevated for receiving the next brick dislodged from the mold.

The magazine 81 for receiving the pallets 50 is located at one end of the track 49 and 40 is inclined to the vertical thereby throwing the pallets 50 at an inclination to the vertical, so that the greater part of the weight of a pile of pallets is sustained by the lower wall of the magazine as will be readily understood. This arrangement also greatly 45 facilitates the withdrawal of the pallet at the bottom of the pile by the projections 56 of the endless carrier. As the lowermost pallet of the pile moves forward the weight 50 of the pile in tilting is sustained by the lower or rear wall of the magazine 81 as indicated most clearly in Fig. 8.

Each of the molds is closed at its bottom by a slide 82 which is retained in place and 55 directed in its reciprocating movements by suitable guides disposed upon the under side of the rotary table 8. The slides 82 are moved outward to permit the discharge of the bricks and are moved inward to close 60 the bottoms of the molds and held in such inner position during the time that the molds receive a charge of material, while such material is being compressed to form the brick, and during the movement of the 65 brick from the compressing mechanism to

the point of discharge. Each of the slides is provided at its outer edge with a depending projection 83 which engages a cam 84 to move the slide outward and a cam 85 to move the slide inward. The cams 84 and 85 are 70 reversely disposed and occupy a fixed position, being supported by the main frame and carried by brackets projecting laterally from the pedestal 1. The slides or mold bottoms 82 remain closed until the molds 75 approach a position in line with the ejector when such slides are moved outward and fully uncover the molds when the latter reach a position in line with the ejector. After delivery of the brick from the mold, 80 as the table moves forward the slide is closed or moved inward by the projection 83 riding upon the cam 85. To reduce the friction to the smallest amount possible the depending projection 83 may consist of a 85 pin or stud having a roller or sleeve fitted thereon to bear against the cams 84 and 85.

After the table 8 has been rotated to bring the molds into proper position with reference to the compressing and ejecting mechanisms, it is desirable to secure the table and prevent possible movement thereof. For this purpose a detent is provided, the same consisting of a head 86 and a shank 87. The head 86 is toothed to engage the toothed edge 90 14 of the rotary table. A bracket 88 projecting from a side of the pedestal 1 is formed with a guide 89 which receives the shank 87 of the detent. A lug 90 projects upwardly from the outer end of the horizontal portion of the bracket 88 and receives an adjusting screw 91. An expansible helical spring 92 is interposed between the outer end of the shank 87 and the inner end of the adjusting screw 91 and normally serves to 105 hold the detent pressed inward, with its toothed portion in engagement with the toothed portion 14 of the table. A lever 93 fulcrumed between its ends to an arm 94 projecting upwardly from the bracket 88 has 110 one end connected to the shank 87 of the detent. The opposite end of the lever 93 is provided with a projection 95 which is located in the path of a cam 96 secured to the vertical shaft 16. The parts are so proportioned and arranged that when the table is 115 rotated forward by means of the gear wheel 15 the detent is thrown outward, thereby bringing the toothed portion of the head 86 away from the toothed portion 14 of the 120 table. During the forward rotation of the table 8 the spring 92 is compressed and the instant the table reaches a position to bring the molds in register with the compressing and ejecting devices the projection 95 clears the high part of the cam 96, thereby permitting the spring 92 to act quickly to throw the detent into locking engagement with the table to hold the same during the operation of the compressing and ejecting devices. 130

The projection 95 is preferably in the nature of a roller mounted upon a stud or pin carried by the free end of the lever 93 so as to reduce the friction when riding upon the 5 cam 96 to the smallest amount possible.

Each of the molds 9 may be of any size or comprise any number of mold cavities according to the capacity of the machine and the number of bricks to be formed by each 10 operation of the plunger. As indicated most clearly in Fig. 5, the mold 9 is divided by means of partitions 97 to form a plurality of mold cavities 98. As illustrated the mold is divided so as to form eight bricks 15 at one operation. It is to be understood, however, that the number may be increased or diminished as required. It is noted that the upper edges of the partitions 97 are square, this being of advantage in preventing the formation of small pieces which usually drop back upon the face of the bricks and are subsequently compressed by the action of the ejector, thereby forming objectionable spots upon the surface. The 20 plunger head 99 is hollow and is adapted to be supplied with a heating medium such as steam, the latter being supplied thereto from a suitable source by means of a hose pipe 100. The face of the plunger head 99 comprises a plurality of compressing elements 101 which are adapted to enter the respective mold cavities 98. These compressing elements 101 are separated by spaces 102 which are of a size to snugly receive the 25 partitions 97. The lower faces of the compressing elements 101 are protected by means of wear plates 103 which usually consist of hardened steel. The plunger head 99 is usually cast and the wear plates 103 are subsequently fitted to the faces of the compressing elements. The construction is such 30 as to permit any one of the wear plates 103 to be readily replaced when worn or otherwise rendered unfit for effective service.

40 The ejector head 104 is constructed in substantially the same manner as the plunger head 99, as shown most clearly in Fig. 7. Steam or other heating medium is supplied to the head 104 by means of a hose pipe 105 which leads from a suitable source of supply. The parts of the ejector head 104 corresponding to the compressing elements 101 are longer than the corresponding parts of the plunger head 99 so that they may enter 45 the mold to a greater depth and thereby force the bricks from the mold cavities 98. A detailed description of the ejector head 104 is deemed unnecessary as the same is of like construction to the plunger head 99, 50 corresponding parts being designated by the same reference numerals.

In the operation of the machine the pallets 50 are placed in a pile in the magazine 81 and the clay or other brick forming material is supplied to the molds in succession

in any convenient manner, it being understood that such material is supplied to the molds in advance of the operation of the compressing mechanism. When the table 8 has rotated to bring a charged mold in 50 register with the plunger 17 such table is held stationary by means of the detent in the manner stated. At this time the endless carrier 51 is likewise stationary but the compressing and ejecting mechanisms are in operation. While the plunger 17 is descending the platen 18 is rising, the parts being so timed and the eccentrics 23 so constructed that the platen 18 is moved upward 55 against the bottom of the slide 82 before the plunger 17 reaches the limit of its downward movement, such platen 18 being held momentarily in contact with the slide 82 during the completion of the stroke of the plunger 17 in the final compressing of the 60 material to form the bricks. This arrangement of the parts is essential in order to prevent injury to the slide 82 and its guides as also to prevent subjecting the table to unnecessary vertical pressure. Simultaneously with the operation of the compressing mechanism, the bricks previously formed 65 are dislodged from the mold in register with the ejector by the operation of the latter. The bricks after being formed are supported 70 in the molds by means of the slides or bottoms 82, thereby preventing the dragging of the bricks over the bed 7. As the full mold reaches a position in line with the 75 ejector the slide or bottom 82 is drawn outward by the action of the cam 84 in the manner hereinbefore stated and when the mold reaches a position in line with the ejector the slide 82 has been fully drawn out so as to uncover the mold. At this time the 80 ejector begins to descend and the platen 34 commences to rise, said platen being elevated in time to receive the bricks from the mold, thereby preventing any jar or injury 85 to such bricks while in the green state. After the bricks have been received upon the pallet 50 supported by the platen 34, the latter begins to descend, thereby depositing the platen with its load upon the track 49. As the table resumes its forward rotation the endless carrier 51 likewise begins 90 its movement, thereby bringing the next pallet into position above the platen 34 and at the same time removing a pallet from the bottom of the pile contained in the magazine 81. As the upper run or portion of the endless carrier 51 moves toward the left the projections 56 engage the pallet deposited upon the track and moves it forward. It 95 is to be understood that the platen 34 is lowered to such an extent as to clear the pallets 50 and enable the same to pass freely thereover. A roller bed formed of a plurality of rollers 106 is located at the end 100 of the track 49 and inclines outwardly and 105

downwardly therefrom. After the pallets clear the track 49 they are received upon the roller bed 106 and gravitate to the predetermined point of discharge. It is to be understood that the bricks may be delivered from the machine in any preferred way so as to be stacked for drying and baking.

To operate the machine by hand for setting or adjusting the parts to insure a consonance of operation, a spur wheel 107 is secured to the outer end of the shaft 78 and a lever 108 is mounted upon said shaft at one side of said wheel. A double ended dog 109 is pivoted to the projecting end of the lever 108 and is adapted to be moved so that one or the other end thereof may be brought into position to engage the teeth of the spur wheel 107 whereby the mechanism may be moved slightly in one direction or the other as found most convenient to admit of properly adjusting the parts to insure accurate registration of the several members.

It is to be understood that in the formation of a machine of the character and for the purpose herein stated various changes in the form, proportion and minor details of construction may be resorted to without departing from the nature of the invention as claimed.

30 It is proposed to apply to each of the hollow plunger and ejector heads means for carrying off the water of condensation. These means are illustrated most clearly in Fig. 5 and are substantially the same for 35 each of the hollow heads and comprise a pipe 110 constituting a header and a plurality of pipes 111 extending from the pipe 110 to within a short distance of the bottom of the hollow head so as to receive and carry 40 off all the water of condensation when the outlet is open. A hose pipe 112 connects with the pipe 110 to carry off the water of condensation to a suitable point of discharge.

45 Each of the slide plates 82 is formed with openings in coincident relation with the mold spaces when such plates are at the limit of their inward movement. A follower is mounted upon each of the slide plates 82 so as to move therewith and comprises a plate 113 and a plurality of blocks 114 which project upwardly from the plate in position to snugly fit the openings of the slide plate 82 and the mold spaces of the mold 9. The follower is supported and directed in its movements by a plurality of guides 115 depending from the slide plate 82. When the follower is at its lowest position the upper faces of the blocks 114 coincide with the plane of the upper face of the 50 slide plate 82. When the follower is elevated the blocks 114 project upwardly into the lower portions of the mold spaces and compress the material therein. The follower 113 is adapted to be engaged by the 55 platen when the latter is moved upwardly

in the manner hereinbefore stated and such movement occurs simultaneously with the downward movement of the plunger so that the material in the mold is compressed from above and below at the same time.

70

The follower is moved downward preliminary to the outward movement of the plate 82 so as to withdraw the blocks 114 from the mold. The means for depressing or lowering the follower comprise two cams 116 and a pair of pivoted arms 117. A bracket 118 projects outwardly from the pedestal 1 and the arms 117 are pivoted thereto. Each of the arms 117 is provided at its free end with a pair of rollers 119 and 120. These rollers 80 are mounted upon a transversely disposed pin carried by the arm and projecting over opposite edge portions of the plate 113. The rollers 120 are arranged to engage the cams 116. The forward ends of the longitudinal edge portions of the plates 113 are downwardly deflected, as indicated most clearly in Fig. 16 so as to pass beneath the rollers 119 and thereby cause such rollers to ride upon the edge portions of the plates 90 113 and depress the same. This occurs when the rollers 120 ride upon the lower faces of the cams 116. The cams 116 and the arms 117 are disposed upon opposite sides of the followers so as to engage with 95 the plates 113 and effect a lowering of the followers so as to withdraw the blocks 114 from the mold spaces. This operation takes place after the final action of the compressing means and preliminary to the action of 100 the ejector.

It is preferred to operate the table by means of a variable movement which is slow at the beginning then accelerated and finally diminishes. This movement obviates shock 105 and strain on the gearing and connections. Figs. 18 and 19 show gearing for effecting this result. In Fig. 18 the shaft 21 is provided with an elliptic gear wheel 71^a which meshes with an elliptic gear wheel 110 70^a upon the shaft 69 which is geared to the vertical shaft 16 by means of the bevel gearing 67 and 68. In the modification shown in Fig. 19 the shaft 69 is provided with a gear wheel 70^b mounted eccentrically thereon and in mesh with a gear wheel 71^b 115 mounted in an eccentric manner upon a shaft to which the gear wheel 73 is secured and which gear wheel 73 is in turn in mesh with the gear wheel 74 on the shaft 75. It 120 will be understood by reason of the co-operating gears 70^a and 71^a and 70^b and 71^b being mounted in the manner stated, a variable movement is imparted to the rotary table which when traveling from one mold to the other starts slowly, has its movement accelerated and then comes to rest by a gradually diminishing movement, thereby avoiding any shock to the working parts.

As shown most clearly in Fig. 10 the 130

toothed portion 14 of the rotary table is interrupted at regular intervals by portions 14^a which are smooth and made concave, such portions projecting beyond the base line of the teeth so as to engage with the smooth portion 15^a of the mutilated gear 15. The toothed portion of the mutilated gear 15 corresponds with the toothed portions 14 of the rotary table comprised between the interrupted portions 14^a, this being necessary in order to move the rotary table the required distance at each operation thereof. The smooth portion 15^a of the mutilated gear 15 rides upon the smooth concave portions 14^a of the rotary table and holds the latter stationary and in proper position during the operation of the compressing and ejecting mechanisms. As indicated in Fig. 2 there are two compressing mechanisms indicated at A and B. The compressing mechanism indicated at A initially compresses the material placed in a mold and in the forward rotation of the table such mold is supplied with additional material before reaching the compressing mechanism B which imparts the final compression to the material in the formation of the bricks. The initial compressing mechanism A is substantially the same as that embodied in the compressing mechanism B and which has been described hereinbefore in detail. It may be stated that it is not desirable or expedient to provide a platen mechanism to coöperate with the compressing mechanism A although the same may be employed if desired.

During the action of the compressing mechanism indicated at B the follower is elevated by the action of the platen 18 in the manner hereinbefore stated and in the forward movement of the table the follower is depressed by the means 117 and 116 so as to withdraw the blocks or projecting portions of the follower from the mold preliminary to the outward movement of the plate 82 and follower to admit of the bricks being ejected from the mold upon the pallet in the discharge of the bricks from the machine in the manner herein stated.

The endless carrier receives a motion similar to the rotary table, *i. e.* it starts slowly, has its movement accelerated, and is then gradually retarded until it finally comes to rest.

Having thus described the invention, what is claimed as new is:—

1. In a machine of the character specified, the combination of a mold formed with a vertically extending mold cavity open at both ends, a slide mounted upon the mold to travel therewith and adapted to close the bottom of the mold cavity and support the material in the mold, means working above and below the mold to compress material against the slide, means for moving the

slide laterally to uncover the bottom of the mold cavity during a portion of the travel of the mold and permit discharge of the compressed material; and separate means for moving the slide across the mold cavity to close the bottom thereof during the continued travel of the mold whereby it may receive and support another charge of material.

2. In a machine of the character specified, the combination of a mold arranged to travel in a horizontal plane and having an open top and bottom, a slide mounted on the bottom of the mold to travel therewith, a projection depending from said slide, a stationary cam disposed in and extending across the path of said projection to be engaged by the same and effect an opening lateral movement of the slide during a portion of the travel of the mold, and a second stationary cam independent of and arranged reversely to the first-mentioned cam to be engaged by said projection and effect closing movement of the slide during continued travel of the mold.

3. In a machine of the character specified, the combination of a mold arranged to travel intermittently in a horizontal plane and formed with a vertically extending mold cavity, a slide upon the mold to travel therewith and adapted to close the bottom of the mold cavity, means for causing the slide to uncover and cover the bottom of the mold cavity during the travel of the mold, a member arranged below the path of the mold and movable vertically into engagement with the slide for supporting the same during a period of rest for the mold, a second member disposed above the path of the mold and adapted to compress the material in the mold during the interval of contact of the first-mentioned member with the slide, and actuating means for operating the said members.

4. In a machine of the character specified, the combination of upper and lower vertically aligned members adapted to have a vertical reciprocatory movement imparted thereto, a mold arranged to travel intermittently between and across the path of the two members and having a vertically extending mold cavity in position to align with the said members, and a slide carried by and traveling with the mold and movable across the path of travel of the mold to close the bottom of the mold cavity, such slide being supported against the pressure of the upper member by the lower member coming in contact therewith.

5. A machine of the character specified, comprising a bed, a mold arranged to travel upon the bed and provided with a vertically extending mold cavity, a slide carried by and traveling with the mold and arranged to move across the bottom of the mold cavity,

means for moving the slide to uncover the mold cavity, separate means for moving the slide in an opposite direction to close the bottom of the mold cavity, a member disposed beneath the bed and movable into contact with the slide to support the same, and a second member arranged above the mold and movable into the latter for compressing the material therein during the interval that the slide is sustained by the lower member.

6. In a machine of the character set forth, the combination of an intermittently actuated mold, a slidable detent mounted in the plane of the mold and constructed to positively engage the edge of the mold and hold it against movement in either direction, a spring acting on the outer end of the detent and tending to normally hold said detent in engagement with the mold, a lever fulcrumed between its ends and having one end pivoted to the detent, and means acting on the opposite end of the lever for intermittently holding the detent out of engagement with the mold.

7. In a machine of the character set forth, the combination of an intermittently actuated mold, a detent slidably mounted in the plane of the mold to positively engage the edge of the same and hold it stationary between its intervals of movement, a spring normally exerting a pressure upon the detent to move the same in one direction, a tension device acting on said spring, a lever pivoted at one end to the detent, and a cam bearing upon the opposite end of the lever for moving the lever against the tension of the spring acting upon the detent.

8. In a machine of the character described, an intermittently actuated mold provided with cog teeth on its edge, a detent slidably mounted in the plane of the mold and formed with teeth at one end to mesh with the teeth on the mold, a spring normally exerting a pressure upon the detent to hold it in engagement with the mold, a lever having one end pivoted to the detent, and a cam bearing upon the opposite end of the lever for operating the lever against the pressure of the spring coöperating with the detent.

9. In a machine of the character described, the combination of a mold arranged to travel intermittently in a horizontal plane, a vertically movable member disposed above the mold, a platen arranged beneath the mold, a lever having engagement at one end with the platen, said lever being composed of sections having a common fulcrum and extending in opposite directions therefrom, operating means acting upon the opposite end of the lever, and means for varying the angular relation of the sections comprising the lever.

65 10. In a machine of the character de-

scribed, and in combination with a mold, a movable member coöperating with the mold, a lever for actuating such movable member comprising sections having a common fulcrum and extending in opposite directions 70 from the fulcrum, one of such sections having laterally extending spaced ears, adjusting screws mounted in such ears, and a projection extending from the other section of the lever and disposed between and engaged 75 by the adjusting screws.

11. In a machine of the character described, the combination of a mold, a movable member coöperating with the mold, a lever comprising sections having a common 80 fulcrum and extending in opposite directions from the fulcrum, one of such sections engaging the movable member, an adjustable weight connected with the outer end of the other section, a cam engaging the weight 85 carrying section of the lever at a point between the weight and fulcrum and acting in opposition to the weight, and means connecting the inner ends of the sections of the lever for varying the angular relation of the 90 same.

12. In a machine of the character described, the combination of an intermittently actuated mold arranged to travel in a horizontal plane, a track arranged beneath the mold and comprising transversely spaced members, pallets, means for depositing the pallets on the track, an intermittently actuated endless carrier comprising endless belts disposed with their upper runs immediately 100 below the respective track members, and projections at the sides of the endless belts embracing and extending upward at opposite sides of the track members to engage the pallets and convey them along the track. 105

13. In combination with a traveling mold, a follower mounted upon the mold to travel therewith and having a two-fold movement, the one in the plane of the mold to enter and leave the mold and the other lateral with respect to the mold to permit the discharge of the article therefrom.

14. In combination with a traveling mold, a follower mounted thereon to travel therewith, means for moving the follower into and out from the mold, and separate means for moving the follower in a plane parallel with the mold to clear the mold space or to occupy a position opposite and in line with such mold space.

15. In combination with a frame, and a traveling mold mounted thereon, a follower mounted upon the mold to travel therewith, cams upon the mold, and pressers mounted upon the frame and arranged to be engaged by said cams and thereby forced into engagement with the follower to move the same downwardly from the mold.

16. The combination with a frame, and a mold mounted to travel thereon, of a fol- 130

lower carried by the mold, cams upon the mold at the sides of the follower, presser levers pivotally mounted upon the frame, and oppositely extending lateral projections 5 at the free ends of said presser levers, some of the projections being disposed to be engaged by the said cams and the other projections being disposed to bear upon the follower when the first-mentioned projections 10 are engaged by the cams.

17. In a machine for the purpose set forth, the combination of a supporting frame, a mold mounted to travel thereon, a plurality of partitions within the mold, a 15 slide mounted on the bottom of the mold to travel therewith and movable radially with respect thereto, said slide having a plurality of openings adapted to register with the spaces between the said partitions within 20 the mold, a follower carried by said slide, projections on the upper side of said follower adapted to extend through the openings in the slide into the lower portions of the spaces between the several partitions, a 25 platen disposed below the mold and adapted to bear against said follower and raise it

into engagement with the mold, means for withdrawing the follower from the mold, means for shifting the slide laterally, and a plunger arranged to enter the upper portions of the spaces between the several partitions within the mold. 30

18. In combination with a mold, a plate disposed at the bottom of the mold and adapted to have a lateral movement imparted thereto, and a follower mounted upon the plate and having a movement toward and away from the mold to enter or leave the same. 35

19. In combination with a mold, a laterally movable plate, disposed at the bottom of the mold, means for moving such plate laterally, a follower mounted upon the plate, and independent means for imparting a movement to the follower to cause the same 40 45 to enter and leave the mold.

In testimony whereof I affix my signature in presence of two witnesses.
